[57] CLAIM

The ornamental design of a spray wand, as shown and
described.

DESCRIPTION

FIG. 1 is a front elevational view of a spray wand showing
my new design;

FIG. 2 is a right side elevational view thereof;

FIG. 3 is a top plan view thereof;

FIG. 4 is a bottom plan view thereof;

FIG. 5 is a rear elevational view thereof;

FIG. 6 is a left side elevational view thereof; and

FIG. 7 is an enlarged scale cross-sectional view taken
on line 7—7 of FIG. 2.

*Fig. 1.**Fig. 2.**Fig. 3.**Fig. 7.**Fig. 4.**Fig. 5.**Fig. 6.*
